UNITED STATES PATENT OFFICE

HARRY D. CLINTON, OF JOHNSON CITY, NEW YORK

TENSION DEVICE

Application filed November 11, 1930. Serial No. 494,990.

This invention relates to tension devices and aims to provide improved means for tensioning yarn in feed operations such as warping and winding, especially where the feed is rapid and tends to increase the gatherings or discharge of lint from the yarn at points of friction for tension purposes.

It will be best understood by description with reference to the attached drawing illustrating one practicable embodiment in the form of a bracket attachable to a warping creel.

In said drawing:

Fig. 1 is a plan view representing a strand of yarn passing deflectively between tensioning elements of the improved character;

Fig. 2 is a sectional side elevation taken on the line 2—2 of the first figure and showing the yarn in feed passage between said elements; and

Fig. 3 represents one of the tensioning elements in plan and side elevation respectively.

The illustrative device comprises a pair of cup-like or frusto-conical discs 4 and 5 fitting substantially one within the other and movable independently on the same axis as common to devices of this kind.

Being apertured centrally for the latter purpose, they fit loosely over a retaining or guide post 6 disposed upright in this instance from a special form of bracket 7 attachable to a support. As the special form of this bracket is not an important feature of the invention, there is no occasion to describe the same in detail, but it may be remarked that said bracket provides guides and additional friction surfaces for the yarn where such are desired, as for example in certain warping operations.

The use of discs slidable on a post and yielding one from another against weight or spring action is of course an old expedient for tensioning yarn drawn therebetween and no claim to the idea broadly is made. Most prior devices of the kind however are subject to the objection of causing a discharge and gathering of lint from the yarn passing therethrough, especially at the very high speeds attainable by comparatively recent improvement in methods of warping. Such gather-

ings of lint tend to attach to the yarn feeding between the discs and form what is known as "slubs", which give rise to breakage and defects in the yarn and in cloth woven therefrom. In my prior U. S. Patent 1,762,049 dated June 3, 1930, is disclosed a tension device of related character designed to eliminate these lint gatherings by dropping through such particles as are not thrown off by centrifugal force of rotation under action of the feeding yarn. The present invention is a further development providing means minimizing if not entirely eliminating the discharge of lint from the yarn while tensioning it properly at high as well as low rates of feed.

This is accomplished by providing one of the discs with a tubular axial extension 8 through the other and engirdling the common retainer post for a liberal extent beyond the other's plane. It is applied in this instance to the upper or outer disc (4), which in the illustrative device moves away from the other disc (5) as the yarn is drawn therebetween. Fitted loosely around or over the post and within the central aperture of said other disc, it allows free-play movement of the two discs independently while serving also to guide and steady the one.

The other disc (5) is rested on an accommodating ledge 9 in the bracket for holding in place without need of guidement by the retainer post, since it has little if any axial movement although free to rotate by action of the yarn thereon. This permits its central aperture to be of a size leaving liberal space between it and said extension of the first disc, so that any lint particles may drop out through underlying web-openings 10 in the bracket (see Fig. 2).

A strand 11 of yarn is shown feeding deflectively between the discs as from a loaded spool to a warp beam. While ordinarily guided to and from these tensioning elements, it is not so represented here because of the numerous ways and means of so doing.

As in other devices of the kind, the discs serve to hold up the strand when slackened from interrupted operation and to tension it during feed. Likewise, one of said discs (in

this instance the upper) will be moved away from the other by the tautened yarn bearing thereunder during feed, but acts to hold the yarn down yieldingly against said other by 5 weighting or spring-depression variable according to the desired tension. In feeding, the yarn of course tends to rotate the discs by the light friction therewith.

As distinguished from other devices however, the aforescribed extension of the 10 movable disc shields the retainer post to prevent contact of the yarn therewith, even though it may move said disc quite far away from the other. The yarn accordingly bears 15 or deflects instead against this roller-like part rotating easily with the disc. Such obviation of rub against a stationary element or surface between the discs minimizes the friction and so reduces the wear on the yarn as to 20 virtually eliminate its discharge of lint particles even at the highest rates of feed, while tensioning the yarn as effectually as any similar device lacking this feature.

Such new lint particles as may be discharged are either thrown off by centrifugal 25 force of disc rotation or dropped out through the openings below the lower or inner disc (5) as previously stated.

It is believed the advantages of a device according to this invention will be apparent to 30 anyone familiar with the textile industry and art, without necessity for further description. Obviously also, other embodiments with various changes in form and arrangement of parts 35 may be made without departing from the scope of the invention, as for example, the retainer post may be of circular cross-section instead of square with rounded corners as shown in this instance, or the lower rather 40 than the upper disc may carry the tubular axial extension. Further, the discs themselves might be given a shape similar to those shown in my aforesaid prior Patent No. 1,762,049 dated June 3, 1930. The appended 45 claims are therefore not intended to limit the invention to the specific device or form thereof herein illustrated.

Having thus described my invention, what I claim as new and desire to secure by Letters Patent of the United States is:

1. A yarn tensioning device, comprising a post and a pair of cup-like frusto-conically shaped discs centered thereon between which the yarn is drawn; one of said discs being 55 adapted to fit within the other and having an axial tubular extension through said other at a substantial spacing from the surrounding edge thereof in sliding fit upon said post.

2. A yarn tensioning device, comprising a 60 post, and a pair of rotatable frusto-conically shaped discs centered on said post in fit one within the other between which the yarn is tensionally drawn with capability of forcing them substantially apart; the inner of said 65 discs having an axial tubular shank extending

through and beyond the outer one at a substantial spacing from the surrounding edge thereof and fitted slidably on the post serving as a guide therefor.

3. In a yarn tensioning device, embodying 70 a post, a pair of frusto-conically shaped and centrally apertured discs rotatably centered on the post in fit one within the other between which the yarn is frictionally drawn with capability of forcing them substantially 75 apart under tension; the inner of said discs having a tubular axial extension through and beyond the outer one at a substantial spacing from the surrounding edge thereof and slidably fitted on the post serving as a guide 80 therefor against which the yarn in feeding between the discs may bear in rotative action thereupon without touching the post however much they may be forced apart.

4. A yarn tensioning device, comprising a 85 support bracket having a post extending rectangularly therefrom, and a pair of centrally apertured frusto-conically shaped discs rotatably centered on the post in fit one within the other between which the yarn is frictionally drawn with capability of forcing them 90 yieldingly apart under tension; the outer of said discs being peripherally supported over an opening through the bracket and the inner of said discs being guided on 95 said post by a tubular axial extension thereof slidably fitting on the post in projection through and beyond the outer disc and at a substantial spacing from the surrounding edge thereof over the aforesaid opening in 100 the bracket.

In testimony whereof I affix my signature.
HARRY D. CLINTON.
